(57) **CLAIM**

The ornamental design for a bottle combined with wrapper, as shown and described.

DESCRIPTION

FIG. 1 is a top perspective view of a bottle combined with wrapper showing our new design.

FIG. 2 is bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The even broken line shown in FIGS. 1, 3, 5-7 show perforation lines on the bottle wrap which form a part of the claimed design.
